TOY BLOCK

Gideon R. Kreider, Jr., Lebanon, Pa.

Application March 27, 1937, Serial No. 133,315

5 Claims. (Cl. 46—24)

This invention relates to toy blocks and particularly to a hollow open-end block formed from paperboard, fibreboard or the like.

Children's toy blocks, such as are commonly used for purposes of instruction and entertainment, are often formed in the form of hollow cubes or prisms having open ends. Where such blocks are formed from thin pieces of wood, the blocks are relatively heavy and hard and are quite expensive to manufacture. Where it has been attempted to form blocks of paperboard, fibreboard or the like, they have been too flimsy and destructible and it has been difficult to make them sufficiently rigid and rugged to withstand the severe usage to which they are customarily put.

According to the present invention, an open end hollow block of prismatic shape is constructed with laminated walls of novel construction which provides the desired rigidity. The block includes an outer shell formed from a paperboard blank suitably scored to provide mitered corners, the ends of the blank being secured together by suitable means, such as a strip adhesively applied to the ends to maintain the blank in set-up tubular shape. A liner structure is disposed in the shell and includes a U-shaped liner member formed from paperboard and having side panels extending over opposite sides of the shell and an end panel closing one end of the shell. A second and similar liner member is disposed in the shell with its end panel overlying the first end panel and its side panels overlying the second pair of opposite side walls. Where additional thickness and rigidity of the end wall is desired, an end piece is interposed between the end panels of the liner members. The liner members are secured in the shell in a suitable manner, as by an adhesive, and a suitably colored and/or decorated wrapper is applied to the block thus formed. The liner blanks may be formed from blanks having wrappers or liners applied to one face thereof thus dispensing with the necessity for wrapping the inside of the block.

The blanks forming the shell and liners are so formed that, when in position to form the block, the fibres or "grain" of the side walls of the shell extend perpendicular to the fibres or "grain" of the liner members, thus providing additional rigidity. In a similar manner the end panels forming the end wall are arranged with their fibres perpendicular. Additional rigidity along the edges of the block is provided by abutting the end edges of the side panels of one of the

liner members against the inner faces of the side panels of the other liner member.

An object of the invention is the provision of a child's toy block formed of paperboard, fibreboard or the like, which is strong and rugged and has a laminated wall structure which is substantially more rigid than a wall structure formed from unlaminated material of the same thickness.

Another object of the invention is the provision of a toy block which is formed from very simple and economical blanks which are readily assembled and which provide a sturdy, rigid structure.

Another object of the invention is the provision of a toy block having a novel form of wrapper applied thereto, which is economical as to material, and which can be quickly and easily applied to form a neat and attractive covering for the block structure.

Various other features and advantages of the invention will be apparent from the following particular description and from an inspection of the accompanying drawings.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which:

Fig. 1 is a plan view of a blank used in constructing the shell portion of the block;

Fig. 2 is an enlarged cross-sectional view taken along line 2—2 of Fig. 1 and showing particularly the manner of scoring the blank;

Fig. 3 is a top plan view of a blank used in forming one of the liner members;

Fig. 4 is a similar view of an identical blank used in forming the other of the liner members;

Fig. 5 is a top plan view of a blank used in forming the top wall of the block;

Fig. 6 is an exploded and somewhat diagrammatic view showing the shell and liner members and illustrating the relation between these members when the block is assembled, the lower liner being shown with one of its side wall sections bent downwardly in order to illustrate the structure more clearly;

Fig. 7 is an enlarged view showing a vertical cross section taken through a block formed in accordance with the invention;

Fig. 8 is a plan view of a side cover blank;

Fig. 9 is a plan view of an end cover blank;

Fig. 10 is an exploded perspective view showing the block, with the side cover blank and top cover blank with the blanks in positions which they respectively assume during the wrapping of the block, this view being only illustrative and not necessarily a showing of any particular stage in the wrapping operation; and

Fig. 11 is a perspective view showing a set of four blocks formed in accordance with the invention and partially telescoped one within the other.

In the following description and in the claims, various details will be identified by specific names for convenience, but they are intended to be as generic in their application as the art will permit. Like reference characters denote like parts in the several figures of the drawings.

In the drawings accompanying and forming part of this specification, certain specific disclosure of the invention is made for purposes of explanation, but it will be understood that the details may be modified in various respects without departure from the broad aspect of the invention.

25 The block consists essentially of a heavy outer shell of tubular form and one or more liner members disposed within the shell and serving to close one end of the tubular shell and reinforce the side walls thereof; usually, a wrapper is applied 30 to the block for improving the attractiveness.

Referring particularly to Fig. 1, the shell is formed preferably from a single blank 5 of relatively heavy material, as for example, paperboard, fibreboard or the like. The blank may be 35 formed of stock of any desired thickness, but I have found that a stock ranging from about $\frac{1}{8}$ to about $\frac{1}{4}$ of an inch suitable for many sizes of blocks. A plurality of relatively deep 90° grooves or cuts 6, 7 and 8 are formed in the blank and divide it into side panels 1, 2, 3 and 4. The end edges 9 and 10 are beveled at 45° whereby to provide a mitered corner when the blank is set up. Preferably, the sides of the grooves 6, 7 and 8 and the beveled edges 9 and 10 extend throughout the major portion of the thickness of the blank, but sufficient material is left to provide a 45 flexible connection between the panels, along the grooves 6, 7 and 8.

The blank 5 is set up to form a tubular shell by bending the sections at right angles about the 50 lines 6, 7 and 8 and bringing the beveled edges 9 and 10 into abutment, as shown particularly in Fig. 6. The abutting edges of the side panels 1 and 4 are secured in a suitable manner, as for example, by the adhesively attached strip 14, 55 thereby forming a tubular shell 15.

Referring now to Fig. 3, a liner member 20a is formed from a rectangular blank, such as paperboard, which preferably generally is of less- 60 er thickness than the shell blank. For example, the liner blank may be approximately one-half the thickness of the shell blank. The liner blank is provided with spaced score lines 21 and 22 which divide the blank into side sections 23 and 25 and an intermediate top or "end" section 24. The liner blank may be formed of stock which is suitably calendered and/or colored on at least one side thereof, but preferably the blank is cut 65 from stock having a wrapper 26 of calendered and/or colored material secured to one face thereof.

70 Preferably, two identical liner members 20a and 20b are provided, for a purpose which will hereinafter appear, the second liner member 20b being shown in Fig. 4.

A top piece 30 (see Fig. 5) is formed from stock which preferably is similar to the stock forming the liner members 20a and 20b and is similarly provided with a wrapper 31. The top piece 30 is dimensioned similarly to the top sections 24 of the liner members 20a and 20b.

Referring to Fig. 6, the block is assembled by folding one of the liner members 20a along the fold lines 21 and 22 with the wrapper 26 on the inner side whereby the liner member assumes a generally U-shaped form. The top piece 30 is then disposed on the bottom panel 24. Thereafter, the liner member 20b is set up in a similar manner to the first liner member 20a and is disposed on top of the top piece 30 but rotated 90° so that the side panels 23 and 25 are disposed between the space of the side panels 23 and 25 of the first liner member.

This assembly of liner members 20a and 20b and top piece 30 is then pressed into the set-up 20 tubular shell 15 until the top panel 24 of the liner member 20a is flush with the lower edges of the shell 15, the side panels 23 and 25 of the liner members 20a and 20b lying against the inner faces of the panels 1, 2, 3 and 4 of the 25 shell 15.

Referring to Fig. 7, it will be seen that the block as thus far assembled has four side walls formed of two-ply material, the total thickness of which is approximately three times the thickness of the liner piece. The wall which is perpendicular to the side walls, and designated herein, for convenience, as the "top" or "end" wall, is of approximately equal thickness to the side walls but is constituted of three plies of material, 30 namely, the two top panels of the liner members 20a and 20b and the top piece 30. The liner members 20a and 20b and the top piece 30 may be secured in the shell 15 by applying an adhesive to the side panels 23 and 25 preferably before the liner members and top piece are inserted in the shell 15.

It will be seen that the side panels 23 and 25 of the liner members 20b fit inside of the side panels 23 and 25 of the liner member 20a. 45 Hence, when the liner members are inserted in the shell 15, and secured thereto, there is an interlocking of the liner members at the corners of the block and the structure is more rigid than if the walls were merely individually laminated. 50

The blanks, employed in forming the liner members 20a and 20b and the blank forming the shell 15, are cut from material in such a way that when the block is assembled, the fibres or "grain" of the material in the side panels 23 and 25 of each of the liner members extend or run perpendicular of the fibres or grain in the corresponding panels of the shell 15. Thus, when the block is assembled and the liner members are secured to the shell, an extremely stiff, rigid block is provided. The top wall and side walls are of substantially equal thickness and are formed of laminated members having the grain extending in perpendicular directions, hence the walls have substantially equal rigidity and are 65 substantially equally rigid both longitudinally and laterally. Thus, the block is not weak in any direction but is capable of withstanding shocks or stresses applied from any direction.

In this connection it will be noted that when 70 the liner members 20a and 20b are assembled, the grain of the end panel 24 of the liner member 20b extends perpendicularly to the grain of the corresponding portion of the liner member 20a. Thus, the top wall of the block likewise 75

has increased rigidity, by reason of the perpendicularity of the fibres in the laminations of the wall.

The block preferably is provided with a suitable covering or wrapper and/or liner which may be of plain color, a contrasting color with the wrappers on the liner pieces or which may be decorated with designs, indicia, scenes or the like, as is customary in toy blocks. The wrapper 5 may take various forms, but for the purposes of illustration, there has been shown herein one novel form of wrapper which has been found to be particularly economical and desirable. This wrapper preferably is formed from two blanks 10 hereinafter and more fully described.

Although the wrapper blanks are shown herein with fold lines and panels indicated, it will be understood that the blanks preferably are not creased or scored prior to being applied to the 20 block and that the indicated fold lines and panels are merely for the purpose of assisting in describing the manner in which the wrapper is applied to the block. However, if it is desired to crease or score the wrapper, especially where 25 the wrapper is of relatively heavy stock, this may be done as indicated, but this is not generally necessary.

Referring to Fig. 8, a blank 99 is formed of a generally rectangular strip of paper which is 30 highly calendered or glazed on one side and suitably colored or decorated. The wrapper blank 99 is adapted to be folded along the lines 105, 106, 107 and 108 to form side panels 101, 102, 103 and 104 corresponding in size to the outer faces 35 of the side panels 1, 2, 3 and 4 of the shell 15; a lap panel 100 of suitable width extends from the panel 101. Extending from the side panels 101, 102, 103 and 104 are edge flaps 111, 112, 113 and 114 respectively, which are foldable about 40 a line 97. An edge flap 110 extending from the lap panel 100 is also foldable about the line 97. A fold line 98 extends throughout all of the edge flaps 110, 111, 112, 113 and 114 parallel to the line 97.

Cut lines 120, 121, 122 and 123, each having a vertical portion and an inclined portion, separate the respective end edge flaps 110, 111, 112, 113 and 114. These cut lines are so arranged as to provide ears 132 and 133 extending from the flap 112, ears 134 and 135 extending from the flap 113, and an ear 131 extending from the inside edge of the lap panel 110.

Referring to Fig. 9, the blank 199 forming the end wrapper includes an end panel 200 having side flaps 211, 212, 213 and 214 extending from the edges thereof and bendable about score lines 201, 202, 203 and 204. Extending from the end edges of the side flap 212 are tabs 225 and 226 bendable about score lines 221 and 222 respectively, and bendable about the opposite side flap 214 are tabs 227 and 228 bendable about fold line 223 and 224.

Preferably, wrapper 199 is applied to the blank first, the end panel 200 being placed against the 65 end of the block and the side flaps 211, 212, 213 and 214 folded up and secured to the corresponding sides of the block. Thereafter, the tabs 225, 226, 227 and 228 are folded over and secured.

The wrapper 99 is then applied to the block by 70 wrapping it about the block, the fold lines 105, 106, 107 and 108 coinciding with the corners of the block, as indicated in Fig. 10. Thereafter, the edge flaps 111, 112, 113 and 114 are folded across the adjacent edge of the block and down- 75 wardly over the corresponding sides, the fold

lines 97 and 98 coinciding with the outer and inner edges of the side walls respectively.

It will be noted that the cut lines 120, 121, 122 and 123 are of such shape that the inclined portions coincide with the abutting mitered 5 scores in the block blank.

The edge flaps 112 and 114 are folded down against the corresponding inner walls of the block first, the ears 131, 132, 133, 134 and 135 being folded along lines 105, 106, 107, 108 and 10 129 so as to lie against the side walls 101 and 103 adjacent the walls to which their corresponding flaps 110, 112 and 114 are attached. The other edge flaps 111 and 113 are then folded down to overlie their corresponding walls and the ears 15 131, 132, 133, 134 and 135. The straight edges of the edge flaps 111 and 113 coincide with the inside corners of the block.

The wrappers 99 and 199 may be glued and applied by hand or suitable automatic machinery 20 in a suitable manner which will be understood by those skilled in the art.

A set of blocks, such as shown in Fig. 11, may be constructed in the manner above described, each block being of sufficient size to permit telescoping therein of the next smaller block. For example, the block D fits in the block C, the block C in the block B, the block B in the largest block A, thus providing a convenient and neat appearing assembly. Also, this arrangement of 30 blocks permits the blocks to be stacked one upon the other by the child.

It will be understood that although a block of cubical form has been shown and described herein for the purposes of illustrating the invention, the invention is not thus limited. By suitable design of the blanks, the side walls and/or the end walls of the block may take the form of rectangles and the block may be relatively short or relatively long in any direction as desired.

From the foregoing it will be seen that the invention provides a block which can be formed from very simple and economical blanks. It will be noted that the blanks for forming the shell 45 and liner members may be of simple rectangular form and thus can be formed with a minimum loss of material. The wrapper blanks similarly may take substantially the form of rectangles and thus also are very economical. The block 50 may be formed of relatively inexpensive paperboard or fibreboard, inasmuch as the construction is inherently rigid and self-reinforcing.

The structure of the blanks is such that the block may be quickly and easily assembled either 55 manually or with suitable automatic machinery, as will be apparent from the foregoing to those skilled in the art. The wrappers may also be applied manually or by automatic machinery and are of such construction that they can be 60 applied economically and easily to form a neat and attractive covering for the block.

While certain novel features of the invention have been disclosed and are pointed out in the annexed claims, it will be understood that various omissions, substitutions and changes may be made by those skilled in the art without departing from the spirit of the invention.

What is claimed is:

1. A rigidly nondeformable toy block of generally prismatic shape having a closed end and an open end, said block including a tubular outer shell having connected side wall panels formed from paperboard material having a thickness greater than one-sixteenth of an inch, a liner 70 75

member formed from paperboard material tightly fitting within said shell and having connected panels extending over a pair of opposite side wall panels and an end of said shell, and a second liner member formed from paperboard material tightly fitting within said shell and having connected panels extending over another pair of side wall panels and said end of said shell, means permanently securing said liner members in said shell, and a wrapper adhesively secured to the exterior of said outer shell.

2. A rigid set-up toy block of generally prismatic shape having a closed end and an open end, said block including a tubular outer shell of rectangular cross section having connected side wall panels formed of paperboard material approximately one-eighth of an inch in thickness, a pair of U-shaped liner members formed of paperboard material of less thickness than the thickness of said outer shell, one of said U-shaped liner members having connected side and end panels extending over a pair of opposite side wall panels and an end of said shell respectively, and the other of said U-shaped liner members similar to said first liner member and having its end panel interposed over the end panel of said first liner member and its side panels extending perpendicular to the side panels of said first liner member and extending over another pair of side walls of said shell, a separate end member interposed between the end panels of said liner members, and means securing said liner members in said shell.

3. A toy block including a rigid prismatic body having connected side walls, end wall and an open end, said body member comprising an outer tubular shell formed from paperboard material having enclosing side walls and open ends, a U-shaped liner member of paperboard material having a pair of side panels secured to a pair of opposite side walls of said tubular shell and a second U-shaped liner member having opposite side wall panels secured to another opposite pair of side walls of said shell, and a wrapper secured to said body and including side panels covering

the body side walls, and edge flaps extending across the end edges of said body at the open end, certain of said edge flaps having the end edges extending diagonally across the corners of said end edges and along the inner corners of said side walls and other of said edge flaps having ears underlying said first-named edge flaps.

4. A toy block including a rigid prismatic body having connected side wall, an end wall and an open end, said body member comprising an outer tubular shell formed from paperboard material having enclosing side walls and open ends, a U-shaped liner member of paperboard material having a pair of side panels secured to a pair of opposite side walls of said tubular shell and a second U-shaped liner member having opposite side panels secured to another opposite pair of side walls of said shell, an end wrapper having an end panel extending over said end wall and side flanges extending over portions of said side walls, and a body wrapper secured to said body and comprising side panels covering the body side walls and overlying said side flaps, and edge flaps extending across the end edges of said body at the open end, and secured to the inner faces of said side walls, certain of said edge flaps having ears underlying other of said edge flaps.

5. A toy block of rigidly non-deformable prismatic shape having laminated side walls and a laminated closed end wall, said block including an outer tubular shell formed from a rectangular paperboard blank and having connected side walls and open ends, a plurality of liner members each formed from a rectangular paperboard blank and each having a pair of side panels extending over opposite side walls of said shell and an end panel extending over the end of said shell, a separate end reinforcing member formed from a rectangular blank and interposed between the end panels of said liner members, and means permanently securing said liner members in said shell, the fibres or grain of a lamination in each wall being perpendicular to the fibres or grain of another lamination in said wall.

GIDEON R. KREIDER, JR. 45
